UNITED STATES PATENT OFFICE

160,153

CARPET OR SIMILAR ARTICLE

Ruth S. Feirberg, New York, N. Y., assignor to Stephen Rug Mills, Inc., New York, N. Y., a corporation of New York

Application January 10, 1949, Serial No. 153

Term of patent 3½ years

(Cl. D92—4)

To all whom it may concern:

Be it known that I, Ruth S. Feirberg, a citizen of the United States, residing at New York city, in the county of the Bronx and State of New York, have invented a new, original, and ornamental Design for a Carpet or Similar Article, of which the following is a specification; reference being had to the accompanying drawing, forming a part thereof.

The figure is a plan view of a carpet or similar article, showing my new design.

A complete design unit is outlined by the dot and dash lines, which unit is repeated over the material, as indicated.

Only one design unit is shown in full lines for convenience in illustration.

I claim:

The ornamental design for a carpet or similar article, substantially as shown and described.

RUTH S. FEIRBERG.
